[57] CLAIM

The ornamental design for a cosmetic compact, as shown and described.

DESCRIPTION

FIG. 1 is a top plan view of a cosmetic compact showing our new design;

FIG. 2 is a top plan view of a second modified embodiment;

FIG. 3 is a top plan view of a third modified embodiment;

FIG. 4 is a front elevational view of all embodiments;

FIG. 5 is a rear elevational view of all embodiments;

FIG. 6 is a left side elevational view of all the embodiments, the side opposite being a mirror image of the side shown;

FIG. 7 is a bottom plan view of all embodiments;

FIG. 8 is a perspective view of the first disclosed embodiment; and,

FIG. 9 is a perspective view thereof shown in an open condition.

The broken line showing of the makeup brush is for illustrative purposes only and forms no part of the claimed design.

The partially disclosed embodiments represented in FIGS. 2 and 3 are identical in all respects to the first disclosed embodiment, except for the arrangement of the interior compartments.

FIG. 3

FIG. 7

FIG. 2

FIG. 5

FIG. 1

FIG. 4

FIG. 6

FIG. 8

FIG. 9
